UNITED STATES PATENT OFFICE.

JOSEPH T. HEFNER, OF TOPEKA, KANSAS.

MAIL-BAG RECEIVING AND DELIVERING APPARATUS.

1,408,595.

Specification of Letters Patent.

Patented Mar. 7, 1922.

Application filed May 21, 1920. Serial No. 383,053.

To all whom it may concern:

Be it known that I, JOSEPH T. HEFNER, a citizen of the United States, residing at Topeka, in the county of Shawnee and State 5 of Kansas, have invented certain new and useful Improvements in Mail-Bag Receiving and Delivering Apparatus, of which the following is a specification.

This invention relates to mail bag receiving and delivery apparatus.

The object of the invention is to provide simple and efficient mechanism for transferring mail from a fast moving train to a station crane and vice versa.

Another object is to provide apparatus of this character carried by the train and adapted to be easily swung into and out of operative position by a person within the car.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Fig. 1 represents a side elevation of a railway car equipped with this improved apparatus and a station crane positioned for cooperation therewith.

Fig. 2 is a horizontal sectional view of the invention.

Fig. 3 is an end elevation showing the crane apparatus and the station crane in operative relation and in the act of transferring mail.

Fig. 4 is a detail vertical section taken on the line 4—4 of Fig. 2.

Fig. 5 is a detail longitudinal section taken on the line 5—5 of Fig. 2.

Fig. 6 is a detail transverse section taken on the line 6—6 of Fig. 2.

Fig. 7 is a detail vertical section taken on the line 7—7 of Fig. 1; and

Fig. 8 is a detail horizontal section taken on the line 8—8 of Fig. 1.

In the embodiment illustrated a station crane 1 is employed and a train carried crane 10. The station crane comprises, in the form shown an upright or standard composed of adjustable sections 2 united by couplings 3, although obviously it may be

made in a single member if found desirable to do so.

A T-coupling 4 is carried by the standard 1 and supports a laterally extending arm 60 5, which carries at its free end another T-coupling 6 in which is mounted a bag supporting bar 7 arranged at right angles to arm 5 and extending on opposite sides thereof being notched in its upper face, as 65 shown at 8, to receive and support mail bag carrying rings 9, which are to be delivered to the train carried crane. This bar 7, as is shown in Figs. 1 and 2 is positioned parallel with the track on which the train is 70 to travel, and is so located as to cooperate with the crane 10 carried by the train.

The train carried crane comprises a vertically disposed rod 11 mounted to turn in suitable bearings secured at the top and bottom of the door way of a car. This rod 11 has its central portion threaded to receive a correspondingly threaded coupling 20 presently to be described.

A collar 12 is secured to the lower end 80 of the rod 11 by a set screw or other suitable means, and a block 13 is mounted for vertical movement on the lower end of the rod and between which and said collar 12 is disposed a coiled spring 19 which exerts 85 its tension to force block 13 downward. This block 13 has a stud 14 depending from its lower face which is designed to enter a socket in a base 15 for securing the rod 10 in adjusted position and holding it against 90 turning. The lower face of this block 13 is recessed to receive one end of a lever 17, which end is apertured for the passage therethrough of the rod 11. This aperture 18 of lever 17 is made sufficiently large to 95 permit the free turning of the rod 11 without affecting the lever, as is shown clearly in Fig. 4.

A roller 16 is mounted on the base 15 and operates as a fulcrum for lever 17, the free 100 end of which projects rearwardly into the car and is designed to form a pedal which when depressed will raise block 13 against the tension of spring 19 and release said block 13 from the base 15 to permit the rod 11 to be manually rotated for swinging the bag carrying portion thereof either into or out of the car C.

The coupling 20 which has threaded engagement with rod 11 has an arm 21 extending radially therefrom and is connected by a brace 22 with the upper portion of rod

11 by a collar 23. Removably mounted on the outer end of arm 21, is a bar 24, which is secured to said arm by a pin 27 passing transversely through the arm and the bar 5 as is shown clearly in Fig. 6.

The bar 24 which is secured midway its ends to the arm 21 is designed to be positioned in a horizontal plane and carries at one end a pivoted stop 25 mounted on a collar 10 26. This stop 25 has its free end extending inwardly and of sufficient weight to cause it to drop normally into closed position, its free inner end being beveled inwardly, as is shown at 25^a to cause a mail bag ring 9 to 15 raise it and pass under it, should there be a tendency for this ring to slip off the end of bar 24.

The other end of this bar 24 is cut out on its inner face to form a recess 28, in which is 20 mounted a movable jaw 29 fulcrumed at 30, intermediate of its ends. A coil spring 31 is arranged between the inner face of the rear end of jaw 29 and the opposed face of the cutout portion of bar 24, and exerts its 25 tension to normally force the front end of jaw 29 into clamping engagement with bar 24. The opposed faces of jaw 29, and the cutout portion of bar 24 are provided with 30 registering notches 32 which are designed to receive the shanks 9^a of the mail bag carrying rings 9, as is shown clearly in Figs. 2 and 8. Any desired number of these registering notches may be employed according 35 to the number of mail bags B, it is desired to deliver at a single station. The shanks 9^a of the mail bag rings 9 are shown provided with loops 9^b, see Fig. 7, so that when the shank 9^a is clamped between jaw 29 and bar 24 upward movement of the mail bag ring 40 will be prevented.

In the use of this apparatus the station crane, the parts of which are stationary, may have hung on the bar 7, thereof, a bag B, it being positioned on said bar according to 45 the direction in which the approaching train is traveling, the train being shown moving toward the right in Figs. 1 and 2. Before the train reaches the station, the mail clerk opens jaw 29 of the train crane which is then 50 in the position shown in dotted lines in Fig. 2, and places in one pair of the registering notches thereof, the shank 9^a of a mail bag carrying ring 9 with the ring positioned above the bar 24, as is shown clearly in Figs. 55 1 and 3, so that these rings will be positioned suitably to receive the bar 7 at the station crane. After these bags have been clamped on bar 24, the clerk depresses lever 17 with his foot, thereby elevating block 13 and releasing it from base 15, permitting the rod 11 to be rotated sufficiently to swing the arm 21 and the bar 24 carried thereby outward into the position shown in Figs. 1, 2 and 3 and when the clerk removes his foot from 60 lever 17, the stud 14 on block 13 will enter 65

a socket in base 15, and thus lock the crane in operative position ready to receive and deliver mail bags. As the train approaches the station, the pointed end of bar 24, which carries the pivoted stop 25, will pass 70 through the ring 9 of the bag B supported on the station crane bar 8, and this bar 8 will enter the rings 9 of the bags B, carried by the spring pressed clamping member of bar 24, so that as the train continues its movement, the bag on the station train will be transferred to bar 24 of the car train and the bags on the car train will be forced from between the clamping jaws thereof and transferred to the bar 8 of the station crane. 80

After the mail has been delivered from the car crane and the station mail received thereby, the operator again depresses the lever 17 and swings crane 10 to cause the bar 24 to enter the car C, so that he may remove therefrom the mail bags. The crane then remains in this position until the next station is reached when the operation is repeated.

From the foregoing description, taken in connection with the accompanying drawings, the advantages of the construction and the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

What is claimed is:

1. In a mail bag receiving and delivering apparatus, a vertically disposed rotatable 105 rod, a block mounted for vertical movement on said rod, a support for said rod, cooperating means carried by said support and said block for locking the block against turning, a spring carried by said rod and engaging 110 said block to hold it yieldably engaged in locking position, a lever for moving said block against the said spring to release it from said support, and mail bag receiving and delivering means extending laterally 115 from said rod.

2. In an apparatus of the class described, an upright standard, an arm extending laterally therefrom, a bar carried by the free end of said arm and secured thereto midway 120 its length, said bar extending at right angles from the arm, a collar carried by one end of said bar, a pivoted gravity stop carried by said collar with its free end extending inwardly and inwardly beveled, and a spring 125 pressed clamping jaw carried by the other end of said jaw.

3. In an apparatus of the class described, an upright standard, an arm extending laterally therefrom, a bar carried by the free 130

end of said arm and secured thereto midway said jaw and bar, and a coiled spring for 10 its length, said bar extending at right angles holding said jaw in operative position. from the arm, a collar carried by one end of In testimony whereof I affix my signature to this 10th day of January, 1923, in presence of two witnesses.

5 said collar with its free end extending inwardly and inwardly beveled, the other end of said bar being recessed, a jaw pivoted intermediate its ends in said recessed portion, registering notches in the opposed faces of

JOSEPH T. HEFNER.
